CONTAINER FOR COSMETICS OR THE LIKE

John W. Pfrommer, Cheshire, Conn., assignor to The International Silver Company, Meriden, Conn., a corporation of Connecticut

Filed May 5, 1967, Ser. No. 6,961

Term of patent 14 years

(Cl. D86—10)

FIG. 1 is a rear perspective view of a container for cosmetics or the like showing my new design in closed condition;

FIG. 2 is a rear elevational view;

FIG. 3 is a side elevational view taken from the left of FIG. 2;

FIG. 4 is a side elevational view taken from the right of FIG. 2;

FIG. 5 is an elevational view taken from the side opposite that shown in FIG. 2;

FIG. 6 is a top plan view;

FIG. 7 is a bottom plan view; and

FIG. 8 is a front perspective view in partially open condition.

I claim:

The ornamental design for a container for cosmetics or the like, substantially as shown.
